(57) **CLAIM**

The ornamental design for a hanger with headwear clips, as illustrated and described.

DESCRIPTION

FIG. 1 is a top perspective view of a hanger with headwear clips, illustrating the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken-line disclosure of elements is understood to represent portions of the article in which the design is embodied, but which form no part of the claimed design.
